UNITED STATES PATENT OFFICE.

THOMAS HARRISON, OF WESTON, ONTARIO, CANADA.

TOOTHBRUSH.

1,367,385.

Specification of Letters Patent.

Patented Feb. 1, 1921.

Application filed March 27, 1920. Serial No. 369,309.

To all whom it may concern:

Be it known that I, THOMAS HARRISON, of Weston, in the county of York, Province of Ontario, Canada, have invented certain new 5 and useful Improvements in Toothbrushes, of which the following is a specification.

My object in the present invention is to devise a tooth brush that can be taken apart so that it may be quickly and thoroughly 10 cleaned. I attain my object by dividing the bristle carrying head of the brush longitudinally between the rows of bristles and by making the portion of the head carrying an intermediate row of bristles removable. 15 The end of the removable portion is adapted when moved longitudinally of the brush to engage and hold in proper relative position the ends of all the parts of the head. This movement is obtained by the interengagement of the sides of the parts of the 20 head substantially as hereinafter more specifically described and illustrated in the accompanying drawings in which—

Figure 1 is a plan view of my improved 25 tooth brush looking at the bristle side thereof, the parts being in position for use;

Fig. 2 a similar view showing the parts released ready for the removal of the separable part;

Fig. 3 a side elevation showing the parts 30 in the same position as in Fig. 2;

Fig. 4 an end view of the brush on an enlarged scale; and

Fig. 5 a cross section on the same scale 35 taken on the line *a—b* in Fig. 1.

In the drawings like numerals of reference indicate corresponding parts in the different figures.

1 is the handle of the tooth brush, which, 40 as usual, has the head 2 formed at one end. The head is split longitudinally between the rows of bristles on a plurality of planes of division to form an entirely separate intermediate part 3 and a plurality of outer parts 4. The lines of division are preferably extended well into the handle to give sufficient 45 flexibility to the outer members so that they may be sprung apart as indicated in Fig. 2. The separate part 3 is movable longitudinally 50 of the brush as hereinafter described and has its outer end formed with laterally extending hooks 5 adapted to fit over the ends of the outer parts 4 to lock them against lateral displacement. It is also preferable to arrange the hooked end so as to

prevent displacement of the parts in a direction parallel to the bristles. This is effected by forming grooves 6 in the ends of the parts 4 in which the hooked end 5 may engage as shown. To secure the longitudinal movement of the part 3, I provide the sides of this part with one or more inclined planes 7 adapted to be engaged by a corresponding plane or planes 8 on one or more of the outer parts 4. It is evident that if 60 the part 3 be placed in position and the parts 4 pressed together to engage the planes 7 and 8 that longitudinal movement of the part 3 will be produced as desired. To secure as much lateral movement as possible of the planes 8, they are located at some distance from the ends of the divisions between the parts, which are remote from the head, and, of course, the planes 7 are correspondingly located. When the parts 65 are pressed together to the position shown in Fig. 1, they are held in that position by the slide 9 movable longitudinally of the handle.

On the separate part 3 I prefer to form a 80 button 10 by which it may be moved and handled, and which may serve also as a stop to limit the movement of the slide 9 toward the head of the brush. It is evident that at any time by slipping back the slide that the 85 part 3 may be removed and that each row of bristles is then completely exposed so that the roots of the bristles may be very conveniently and completely cleaned.

It will be noted on reference to Fig. 5, 90 that the parts 3 and 4 are shaped on their adjacent sides to interlock to resist displacement. The part 3 will thus remain in place until deliberately pulled out.

What I claim as my invention is:—

1. A tooth brush split longitudinally of the head between the bristles on a plurality of lines of division, one part being entirely separated; a hooked end on the separated part adapted when moved longitudinally of the brush to engage the ends of the other parts to lock them against lateral displacement; an inclined plane formed on the side of the separate part; and a corresponding plane on the side of one of the adjacent parts adapted to engage the plane on the separate part to draw it longitudinally of the brush to a locking position.

2. A tooth brush constructed as set forth in claim 1 provided with grooves in the

outer parts of the head in which the hooked end of the separate part may engage to prevent displacement of the parts in a direction parallel to the bristles.

5 3. A tooth brush constructed as set forth in claim 1 in which the lines of division between the parts are extended into the handle

and the inclined planes are located intermediate of the ends of the lines of division and at considerable distance from the ends of 10 the lines of division adjacent the handle.

Signed at Toronto, Canada, this 11th day of March, 1920.

THOMAS HARRISON.
